UNITED STATES PATENT OFFICE.

DANIEL J. KELLY, OF CHICAGO, ILLINOIS.

VENTILATOR.

No. 908,576.

Specification of Letters Patent.

Patented Jan. 5, 1909.

Application filed April 18, 1908. Serial No. 427,958.

To all whom it may concern:

Be it known that I, DANIEL J. KELLY, a citizen of the United States, residing at Chicago, in the county of Cook and State of Illinois, have invented certain new and useful improvements in Ventilators, of which the following is a specification, reference being had to the accompanying drawings.

This invention relates to window ventilators of the detachable type and consists of the novel features of construction and the combination and arrangement of parts hereinafter fully described and claimed.

The object of the invention is to provide a simple and practical window ventilator which will permit fresh air to enter the room but at the same time effectively exclude dust and prevent direct drafts; which may be readily adjusted to control the ventilation and which may be quickly and easily arranged in and removed from the window frame.

A further object of the invention is to provide an improved filler strip for use upon the top of the lower sash of the window when the ventilator is arranged in the bottom of the frame, so as to prevent the entrance of air and dirt between the two sashes.

The above and other objects of the invention are attained in its preferred embodiment illustrated in the accompanying drawings, in which—

Figure 1 is a perspective view of the improved ventilator, looking toward the outer side of the same; Fig. 2 is an elevation of the inner side of the ventilator showing it in its normal or open position in full lines and in a collapsed or folded position in dotted lines; Fig. 3 is a vertical section through a window frame showing the ventilator arranged in the same; and Fig. 4 is a detail sectional perspective of a portion of the lower sash and the improved filler strip.

In the drawings 1 denotes a portion of a window frame having upper and lower sashes 2, 3 arranged for sliding movement between the usual stop strips or beads 4.

The improved ventilator may be arranged either at the top or at the bottom of the window frame, but it is preferably arranged at the bottom beneath the lower sash 3, as will be understood upon reference to Fig. 3 of the drawings. The ventilator is in the form of a rectangular frame of any suitable height and of a length corresponding to the width of the sash so that it will be effectively retained in the guideways for the latter formed by the

stop strips 4 of the window frame. To permit the ventilator frame to be readily applied to and removed from the window it is made foldable or collapsible and of four bars or sections 5, 6, 7, 8, pivotally connected at 9 so that the frame may be folded to the shape of a rhomboid, as shown in dotted lines in Fig. 2, to reduce its length and permit it to be inserted between the stop strips 4 on the opposite sides of the window frame. The sections 7, 8 of the ventilator frame form its ends and they are arranged to overlap the ends of the other two sections 5, 6 which form the top and bottom of such frame, the pivots 9 passing through said overlapping ends of the sections and being preferably in the form of rivets. To further reduce the length of the frame when it is collapsed or folded into the form of a rhomboid the inner corners of 75 the top and bottom sections 5, 6 are preferably beveled, as shown at 10.

Arranged over the opening in the ventilator frame is a screen or covering 11 of woolen cloth or other suitable fabric which 80 will permit the fresh air to pass freely through the same but at the same time prevent direct drafts and effectively exclude dust and dirt. The edge of this covering 11 is tacked or otherwise secured to the inner 85 edges of the four sections of the frame, as clearly shown in Fig. 2. Owing to the flexibility of the covering 11 it will not interfere with the folding or collapsing movement of the frame when the ventilator is placed in or 90 removed from the window.

In order to prevent the entrance of drafts and dust between the top of the ventilator and the bottom of the sash 3, a strip 12 of canvas or the like is tacked or otherwise secured to the upper edge of the top section 5, as shown.

In order to permit the ventilation of the room to be effectively controlled and to protect the cloth covering 11 from rain and 100 snow, a guard or solid closure 13 is provided for the opening in the frame. This closure is in the form of a board or plate arranged upon the outer side of the frame and preferably hinged to the top section 5 of the frame 105 so as to swing outwardly and upwardly. Said closure 13 is of substantially rectangular shape and has its top and bottom edges 14 beveled downwardly and outwardly or in the swing direction to correspond with the 110 bevel or inclination of the opposing edges 15 of the top and bottom sections 5, 6 between

which latter said closure is adapted to swing when moved to a vertical position. These bevelled edges of the closure and the top and bottom strips effectively prevent water and snow 5 from working through the ventilator frame when the closure is in its vertical or closed position to cover the opening in the frame and to protect the fabric covering 11. The closure 13 is united to the top section 5 by 10 strap hinges 16, the lower leaves of which are secured to angle metal reinforcing plates 17 arranged upon the ends of the closure 13, as shown in Fig. 1 and their upper leaves are secured to metal reinforcing strips 18 which 15 partially surround the top section 5. Similar reinforcing strips or plates 19 are arranged upon the bottom section 5 to partially surround the same. Said metal parts 17, 18, 19 are employed when the closure and frame of 20 the ventilator are constructed of wood and serve to effectively strengthen the same and prevent the parts from warping and also to strengthen the connection of the hinges 16.

In order to permit the closure 13 to be operated and adjusted from the inside of the 25 room when the ventilator is in position in the window, two operating cords 20, 21 are provided. These cords pass through guide openings 22, 23 formed respectively in the 30 top and bottom sections 5, 6 at their center and the outer ends of said cords are connected to a screw eye or the like 24 arranged upon the outer face of the closure 13 adjacent to its bottom or free edge. The upper cord 20 35 passes through a guide preferably in the form of a screw eye 25 arranged upon the outer face of the top section 5. Any suitable means may be provided for securing the free or inner ends of the cords, particularly the 40 upper one 20, so as to retain the closure 13 at any adjusted position, but as illustrated, a screw eye or hook 26 is arranged upon the center of the inner side of the top section 5 and either or both of the cords may be tied 45 or otherwise secured to such fastening 26. It will be seen that when the upper cord 20 is drawn upon the closure 13 will be swung upwardly and outwardly and may be retained in such position by engaging said cord 50 with the fastening 26. By varying the angle of the closure 13 the amount of ventilation will be effectively controlled. When the cord 20 is released from the fastening 26 the closure 13 will drop by gravity to its closed 55 position in which it may be retained by drawing upon the lower cord 21 and engaging it with the fastening 26.

For the purpose of closing the space between the upper and lower sashes when the 60 ventilator is in position beneath the lower one a filler strip or member 27 is provided. This filler strip is flexibly or hingedly secured to the top of the lower sash 3 and is adapted to bear against the glass of the upper sash, as 65 clearly shown in Fig. 3 of the drawings. It

is preferably constructed, as shown in Fig. 4, of a piece of zinc or other sheet metal 28 and a piece of canvas or fabric 29. In making it the fabric is folded upon itself and its edges are inserted beneath a fold made in the 70 metal. This fold is then pressed down and another fold is made in the metal, thereby effectively interlocking the canvas and metal. The metal is then folded once more upon itself in the opposite direction so that 75 the doubled edge of the fabric projects beyond the last mentioned fold in the metal and may be tacked to the top of the window sash 3 and serve as a hinge or flexible connection for the metal, which latter bears 80 against the window glass, as will be readily understood upon reference to the drawings.

From the foregoing it will be seen that the invention provides an exceedingly simple, practical and handy ventilator which may be 85 quickly and easily applied to and removed from a window, which will effectively exclude dust and dirt and prevent direct drafts, and which may be easily adjusted to vary the ventilation or to stop it entirely without 90 removing the ventilator from the window. The ventilator may be used in houses or buildings of any description, but it is especially suited for sick rooms, hospitals, schools and the like where drafts are dangerous and 95 dust injurious.

While the preferred embodiment of the invention is shown and described in detail, it will be understood that the invention is not limited to the specific construction set forth 100 and that various changes in the form, proportion and minor details may be resorted to without departing from the spirit or sacrificing any of the advantages of the invention.

Having thus described the invention what 105 is claimed is:

1. A window screen or ventilator comprising a covered frame composed of pivotally connected sections and adapted to be folded in a vertical plane to permit it to be 110 arranged between the stop strips of a window frame.

2. A window screen or ventilator comprising an open frame composed of pivotally connected sections, whereby the frame will fold 115 or collapse longitudinally to permit it to be inserted between the stop strips of a window frame and a flexible covering for said open frame.

3. A window screen or ventilator comprising 120 a rectangular frame having top, bottom and end sections pivotally connected, whereby the frame will fold to the shape of a rhomboid, and a flexible covering for said frame, substantially as and for the purpose set 125 forth.

4. A window screen or ventilator comprising 130 a rectangular frame having top, bottom and end sections with their ends overlapping, pivots uniting the overlapping ends of said

sections, the corners of the top and bottom sections being beveled and a flexible covering for said frame.

5. A window ventilator comprising an open rectangular frame having its top and bottom sections or bars formed with their opposing edges beveled outwardly and downwardly, a swinging closure hinged to the top bar to swing outwardly and upwardly and 10 having its top and bottom edges beveled to correspond with the opposing beveled edges of said top and bottom bars, said top and bottom bars being formed with openings, cords passed through said openings and connected at their ends to the closure and means 15 for securing the inner ends of said cords to retain the closure in an adjusted position.

6. A window screen or ventilator comprising an open frame composed of pivotally connected sections and adapted to fold or col- 20

lapse in a longitudinal plane to permit it to be inserted between the stop strips on the opposite sides of a window frame, a porous covering for the opening in said frame, and a solid closure for the opening in said frame. 25

7. A window screen or ventilator comprising an open frame composed of pivotally connected sections and adapted to fold or collapse in a longitudinal plane to permit it to be inserted between the stop strips on the opposite sides of a window frame, a porous covering for the opening in said frame, a solid closure for the opening in said frame hingedly connected to one of its sections and means for operating said closure. 30
